ATTORNEYS

UNITED STATES PATENT OFFICE.

WALLACE W. HEWITT, JR., OF OAKLAND, CALIFORNIA, ASSIGNOR OF ONE-HALF TO
J. STOW BALLARD, OF OAKLAND, CALIFORNIA.

SOCKET WRENCH.

Application filed March 29, 1923. Serial No. 628,446.

To all whom it may concern:

Be it known that I, WALLACE W. HEWITT, Jr., a citizen of the United States, and resident of the city of Oakland, county of Alameda, State of California, have invented new and useful Improvements in Socket Wrenches, of which the following is a specification.

My invention is particularly adapted to socket wrenches whereby a nut which has been removed in the wrench socket may be readily ejected therefrom.

Other objects will appear from study of the drawings and specifications which follow.

These objects I accomplish by forming the socket wrench preferably with a rigid shank whereby it may be rotated in any conventional way and within the socket I preferably mount a plate or diaphragm operable axially therethrough by suitable connections extending through the body of the socket and in a convenient position for operation by the hand of the operator.

By referring to the accompanying drawing my invention will be made clear.

Referring to the drawing:

Fig. 1 shows my invention in its simplest form, partially in cross section.

Fig. 2 shows a preferred form partly in cross section.

Fig. 3 shows an alternate form of the invention partly in cross section.

Throughout the figures similar numerals refer to identical parts.

At 1 is shown a socket of any conventional type as for operating hexagon nuts or cap screws. This is mounted rigidly upon shank 2 or may be solid therewith. At 3 is a diaphragm or flat plate adapted to press against any nut contained within the socket upon depressing the finger members 4, 14, or 24; the finger members being connected in Figs. 1 and 3 by the rods 5 and 15, re-

spectively, to the plate 3 and in Fig. 2 by 45 the rods 6 and 7. At 8 is a spring retaining the plate 3 in its retracted full line position, and which is compressed by depressing the finger member when the said plate is forced into the dotted position 9. 50 Similar springs at 10 and 11 perform a like function for the constructions shown in Figs. 2 and 3.

In the construction shown in Fig. 3 the rod 15 and spring 11 are mounted within 55 the body of the shank 2 and are retained in position by the screw plate 12.

The cross bar 13 extending through the shank 2 and engaging the collar formed finger member 24 operates through the side 60 slots 25, milled in the shank 2, at which time spring 11 is compressed, its other end being retained by the plate 12.

Normally the ejector plate 3 occupies the position shown in full line in the several 65 figures. Upon depressing the finger members 4, 14 or 24, the spring in either case is compressed and the ejector moved into the dotted position 9 ejecting any hexagon shape that may have been retained in the socket. 70

While I have shown and described my wrench as applying particularly to hexagon nuts, it of course will be understood it may be applied to any other form of nut and the invention may be embodied in other 75 constructions and I desire to be understood as claiming all such.

I claim:

A wrench comprising a socket and an operating stem integral therewith, in combination with a plate within the socket said plate movable axially through said socket, a rigid hand operable member fixed to said plate extending through the rear of the socket external to the stem and parallel 85 therewith and spring means normally holding the plate in retracted position.

WALLACE W. HEWITT, JR.
